DUMPING RECEPTACLE

Filed April 27, 1931

FIG. 1.

FIG. 2

INVENTOR,
GLEN M. WILEY,
by

Emmett C. Red
his ATTORNEY.

UNITED STATES PATENT OFFICE

GLEN M. WILEY, OF DAYTON, OHIO

DUMPING RECEPTACLE

Application filed April 27, 1931. Serial No. 533,009.

This invention relates to dumping receptacles such as are commonly used for handling semi-fluid or loose materials, and relates more particularly to what is known as a concrete bucket. Dumping receptacles of this kind discharge through the bottom by gravity and the closure for the discharge opening must be of such a character that it will support the weight of the contents of the receptacle and can be opened and closed by the operator. Hinged closures which open by gravity have not been found practical in dumping receptacles of this kind, particularly for handling concrete, and when a laterally movable or sliding closure is employed the weight of the material thereon, particularly in receptacles of large capacity, is such that the power required to open the same is often in excess of the strength of one man.

One object of the present invention is to provide such a dumping receptacle having a laterally movable closure and operating means therefor which will enable the same to be easily opened.

A further object of the invention is to provide such a dumping receptacle with a swinging closure and an operating lever therefor which, when the closure is in its closed position, will be located alongside of and close to the receptacle where it will be out of the way and will not interfere with the movements of the receptacle.

A further object of the invention is to provide such a receptacle which will be simple in its construction and of a strong durable character.

Other objects of the invention will appear as the device is described in detail.

In the accompanying drawing Fig. 1 is a side elevation, partly in section, of a dumping receptacle embodying my invention; and Fig. 2 is a bottom plan view of the same, partly broken away.

In the drawing I have illustrated one embodiment of my invention and have shown the same as comprising an outer casing 1 which is preferably cylindrical in form and which has secured to the upper portion thereof a bail 2, here shown as a bent bar rigidly secured at its ends to the opposite sides of

the casing. Mounted within this casing is a hopper 3, the upper edge of which is rigidly secured to the casing on a line spaced a considerable distance from the upper end of the casing, the hopper and the upper portion of the casing thus constituting the material receiving part of the structure. The lower end of the hopper terminates above the lower edge of the casing so that the latter constitutes a supporting skirt on which the structure as a whole may rest in an upright position. Preferably the lower edge of this supporting skirt is provided with a reinforcing band, such as the angle iron 4. The lower and smaller end of the hopper has a discharge opening 5 which is here shown as oblong in shape and is formed between downwardly extending flanges 6 which constitute the lower edges of the hopper. The flanges 6 at the ends of the opening are curved, as shown at 7, about an axis extending transversely to the hopper a considerable distance above the discharge opening. This opening is controlled by a laterally movable closure 8 which is preferably in the form of a radial gate, the body portion of which is curved to conform to the curvature of the lower edges of the hopper and the end portions of which are bent upwardly on the outer sides of the hopper, as shown at 9, and have secured thereto arms or straps 10 which are pivotally mounted on studs 11 carried by the hopper, these studs being arranged substantially at the axis about which the edges of the hopper are curved, thus permitting the closure to be close to the edges of the hopper and effectively close the discharge opening but to be swung laterally out of line with the discharge opening to the position shown in dotted lines in Fig. 1.

The operating mechanism for this laterally movable closure may take various forms but preferably comprises a lever mounted on the lower portion of the skirt of the outer casing and having operative connection with the closure. In the form here shown a lever 12 is pivotally mounted at 13 between lugs 14 rigidly secured to the outer side of the casing near the bottom thereof. Rigidly secured to the lever, adjacent to its axis and

preferably formed integral therewith, is an inwardly extending arm 15, the skirt of the casing being provided with an opening 16 through which the arm extends. Pivotally connected with the inner end of the arm 15 are links 17 the opposite ends of which are pivotally connected with the closure 8 and are here shown as arranged on opposite sides of a pivot lug 18 and connected thereto by a pivot pin 19. The arm 15 is of a length considerably less than the length of the lever 12, it being here shown as about one-third of the length of the lever. Consequently the power applied to the lever, when transmitted 10 to the links 17 will be multiplied and a relatively great power applied to the closure to move the same from beneath the material resting thereon. In the preferred arrangement the lever 12 extends normally upward- 15 ly alongside of and close to the outer side of the casing so that it is out of the way and does not in any way interfere with the manipulation of the receptacle. When in this 20 position the arm 15 extends at substantially right angles thereto and the links 18 are in substantial alinement with the arm 15. The arm and the links thus constitute a toggle which, when the closure is in its closed position, will retain the same against outward 25 movement but which when broken by the outward and downward movement of the lever will exert a powerful outward and upward pull on the closure, thus moving the same to its open position, as shown in dotted 30 lines in Fig. 1. The links 17 are preferably angular so that their central portions are slightly lower than their end portions to permit the same to clear the edge of the closure at an intermediate point of movement. The 35 lower end of the hopper and the closure are spaced such a distance above the lower edge of the casing that the closure and its operating mechanism will, in all positions thereof, be above the lower edge of the casing. The 40 skirt of the casing may also be provided with openings 20 spaced circumferentially about the same to provide hand grips, whereby a workman may grasp the receptacle, when the latter is suspended from the cable, to properly 45 position the same for dumping.

While I have shown and described one embodiment of my invention I wish it to be understood that I do not desire to be limited to the details thereof as various modifications 50 may occur to a person skilled in the art.

Having now fully described my invention, what I claim as new and desire to secure by Letters Patent, is:

1. In a dumping receptacle, a casing, a 55 hopper arranged within said casing, having its upper end secured to said casing on a line spaced from the top thereof and having its lower end above the lower edge of the casing and provided with a discharge opening, a 60 swinging closure for said discharge opening,

a lever mounted on said casing and arranged normally alongside of and close to the same, and a toggle having one arm rigidly secured to said lever and having its other arm pivotally connected with said closure. 70

2. In a dumping receptacle, a casing, a hopper arranged within said casing, having its upper end secured to said casing on a line spaced from the top thereof and having its lower end above the lower edge of said casing and provided with a discharge opening, the lower edges of said hopper at opposite sides of said discharge opening being curved about an axis transverse to said hopper, a curved closure for said opening, means for pivotally supporting said closure at the axis of said curved edges, a lever mounted on said casing near the bottom thereof and extending upwardly alongside of said casing, and a toggle having one arm rigidly connected with said lever and having its other arm pivotally connected with said closure. 75 80

3. In a dumping receptacle, a casing, a hopper arranged within said casing, having its upper end secured to said casing on a line spaced from the top thereof and having its lower end above the lower edge of said casing and provided with a discharge opening, a swinging closure for said discharge opening, a lever mounted on said casing and arranged normally alongside of and close to the same, an inwardly extending arm connected with said lever, and means for connecting said arm with said closure, said casing having near its lower end circumferentially spaced hand 90 95 holes. 100

4. A dumping receptacle comprising a hopper having a discharge opening at the lower end thereof and a part arranged exteriorly of and extending below said hopper to form a support for said receptacle, a swinging closure for said discharge opening mounted for movement about an axis arranged above and spaced from said discharge opening, an actuating device mounted on said receptacle exteriorly thereof, and operable mechanism mounted within the supporting part of said receptacle, connected with said closure at a point spaced from the axis thereof and operatively connected with said actuating device to cause the latter to impart swinging movement to said closure. 105 110 115

5. A dumping receptacle comprising a hopper having a discharge opening at the lower end thereof and a part arranged exteriorly of and extending below said hopper to form a support for said receptacle, a swinging closure for said discharge opening mounted for movement about an axis arranged above and spaced from said discharge opening, operable mechanism mounted within the supporting part of said receptacle, connected with said closure at a point spaced from the axis thereof and having a part extending outwardly beyond the supporting 120 125 130

part of said receptacle, and an actuating device operatively connected with the outwardly extending part of said mechanism and extending upwardly alongside of said receptacle.

6. A dumping receptacle comprising a hopper having a discharge opening at the lower end thereof and a part arranged exteriorly of and extending below said hopper to form a support for said receptacle, a swinging closure for said discharge opening mounted for movement about an axis arranged above and spaced from said discharge opening, an arm pivotally mounted on said supporting part of said receptacle, having one end extending inwardly toward said hopper and having its other end extending outwardly beyond said part of said receptacle, an actuating device mounted on said receptacle and operatively connected with the outer end of said arm, and means for operatively connecting the inner end of said arm with said swinging closure.

7. A dumping receptacle comprising a hopper having a discharge opening at the lower end thereof, and a part arranged exteriorly of and extending below said hopper to form a support for said receptacle, a swinging closure for said discharge opening mounted for movement about an axis arranged above and spaced from said discharge opening, an arm pivotally mounted on said supporting part of said receptacle, having one end extending inwardly toward said hopper and having its other end extending outwardly beyond said part of said receptacle, a lever secured to the outer end of said arm and extending upwardly along said receptacle, and means for operatively connecting the inner end of said arm with said swinging closure.

8. In a dumping receptacle comprising a hopper having a discharge opening at the lower end thereof, and a part arranged exteriorly of and extending below said hopper to form a support for said receptacle, a swinging closure for said discharge opening mounted for movement about an axis arranged above and spaced from said discharge opening, an actuating member mounted on said casing exteriorly thereof, and a toggle having one arm operatively connected with said actuating member and having its other arm pivotally connected with said closure.

In testimony whereof, I affix my signature
55 hereto.

GLEN M. WILEY.
